SPINNING REEL

Maurice J. Hammer, Lexington, Mich., assignor to Great Lakes Products, Inc., Lexington, Mich., a corporation of Michigan

Application July 25, 1958, Serial No. 51,939

Term of patent 14 years

(Cl. D31—4)

Figure 1 is a left side elevation of a spinning reel showing my new design;

Figure 2 is a rear elevation thereof;

Figure 3 is a front elevation of the reel; and

Figure 4 is a top plan view of the same.

I claim:

The ornamental design for a spinning reel, substantially as shown.
